CLAIM

The ornamental design for an endoscope, as shown and described.

DESCRIPTION

FIG. 1 is a perspective view of the top, front and one side of an endoscope showing our new design;

FIG. 2 is a top plan view thereof;

FIG. 3 is a front elevational view thereof;

FIG. 4 is an end elevational view of said one end thereof;

FIG. 5 is an end elevational view of an opposite end thereof;

FIG. 6 is a rear elevational view thereof; and,

FIG. 7 is a bottom plan view thereof.

The elements shown in broken lines are for illustrative purposes only and form no part of the claimed design.
